DESIGN FOR AN INKWELL

Roy Eugene Stroh, Brookline, Pa., assignor to The Turner and Harrison Steel Pen Manufacturing Company, Philadelphia, Pa., a corporation of Pennsylvania

Application December 30, 1943, Serial No. 112,123

Term of patent 7 years

To all whom it may concern:

Be it known that I, Roy Eugene Stroh, a citizen of the United States of America, residing at Brookline, in the county of Delaware and State of Pennsylvania, have invented a new, original, and ornamental Design for Inkwells, of which the following is a specification, reference being had to the accompanying drawing, forming part thereof.

In the drawing,

Fig. 1 is a perspective view of an inkwell showing my new design.

Fig. 2 shows a top plan view of the inkwell.
Fig. 3 shows the inkwell in front elevation; and

Fig. 4 shows the elevation of one end of the inkwell.

I claim:

The ornamental design for an inkwell, as shown.

ROY EUGENE STROH.
